(57) **CLAIM**

The ornamental design for an automobile side intake grille, as shown and described.

DESCRIPTION

FIG. 1 is a front perspective view of an automobile side intake grille showing my new design of a left side grill, the right side grille that is not shown is a mirror image; FIG. 2 is a front view thereof;

FIG. 3 is a right side view thereof; and,

FIG. 4 is a top view thereof.

The broken lines in the drawings depict portions of the article that form no part of the claimed design.
